Specification for Design.

Patented July 13, 1920.

Application filed February 19, 1918. Serial No. 218,178. Term of patent 14 years.

To all whom it may concern:

Be it known that we, RICHARD HAWKE ROGERS and PRIMUS OTTO DORER, subjects of the King of England, both residing at 179-185 Great Portland street, London, England, have invented a new, original, and ornamental Design for a Switch-Casing, of which the following is a specification, reference being had to the accompanying drawing, forming part thereof.

Figure 1 is a perspective view of a switch casing illustrating our new design, and Fig. 2 is a side elevation thereof.

The design comprises an annular casing

having a radial flange C near one end thereof. The face thereof is also provided with a wide annular flange A in front of the dial B and which flange is provided with windows A' through which indicating devices may be seen.

We claim:

The ornamental design for a switch casing, as shown and described.

RICHARD HAWKE ROGERS.

PRIMUS OTTO DORER.
